US00D893234S

(12) **United States Design Patent** (10) Patent No.: **US D893,234 S**
(45) Date of Patent: **** Aug. 18, 2020**

(54) **DISPENSER**

- (71) Applicant: **PepsiCo, Inc.**, Purchase, NY (US)
(72) Inventors: **Martin Eduardo Broen**, New York, NY (US); **Stephen Lim**, Chappaqua, NY (US); **Christian Stolarz**, Brooklyn, NY (US); **Martin Ivar Franzen**, Milan (IT)
(73) Assignee: **PepsiCo, Inc.**, Purchase, NY (US)
(**) Term: **15 Years**
(21) Appl. No.: **29/681,360**
(22) Filed: **Feb. 25, 2019**

Related U.S. Application Data

- (63) Continuation of application No. 29/587,477, filed on Dec. 13, 2016, now Pat. No. Des. 841,382.
(51) **LOC (12) Cl.** **07-01**
(52) **U.S. Cl.**
USPC **D7/306**; D7/397; D7/311

(57) **CLAIM**

The ornamental design for a dispenser, as shown and described.

DESCRIPTION

FIG. 1 is a top front perspective view of a dispenser showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

1 Claim, 7 Drawing Sheets
